UNITED STATES PATENT OFFICE.

JULIUS HILBORN, OF NEW YORK, N. Y., ASSIGNOR TO MORITZ COHN, OF SAME PLACE.

CORSET.

SPECIFICATION forming part of Letters Patent No. 254,316, dated February 28, 1882.

Application filed April 26, 1880. (Model.)

To all whom it may concern:

Be it known that I, JULIUS HILBORN, of the city, county, and State of New York, have invented certain new and useful Improvements in Corsets; and I do hereby declare that the following specification, taken in connection with the drawings furnished and forming a part of the same, is a clear, true, and exact description of my invention.

10 One object of my invention is to provide for an easy but close fit in a corset from a point below the arms to and over the hips to the bottom edge of the corset. Another object is to so stiffen the hip-gores in front and rear as to 15 allow them to readily conform to adjacent portions of the body, and yet afford the requisite "staying" properties about the waist and hips; and, still further, to provide for a comfortable freedom of movement by the wearer without 20 impairing the supporting capacities of the corset. In the attainment of these ends in accordance with my invention I am enabled to produce a corset well boned or stiffened throughout and having the desirable staying qualities 25 mainly by the use of short bones, which contributes to economy in manufacture, my improved corset as a whole being preferable to one in which long bones are mainly employed.

The several features of my invention, after 30 being fully indicated in connection with the detailed description, will be made the subject of claims hereunto annexed.

Referring to the drawings, Figure 1 is a front view of a complete corset embodying my invention. Fig. 2 is a side view of one-half of 35 an opened or distended corset embodying my invention.

The cut of the corset so far as relates to the steel section A, breast-gores a, and breast top 40 band, b, is as heretofore.

The front or breast section, B, from the waist upward, is substantially as heretofore; but below the waist it terminates at a point at c.

The complex side and front section, C, extends 45 from the top of the corset downward along one breast-gore to near the waist, and thence downward and diagonally below the breast-section B, and unites with the inner edge of the steel section A.

50 The side section, D, extends from the top of

the corset, beneath the arm, to the lower edge of the corset, over the hip. Below the waist-line it is enlarged to serve as a gore for partially providing for the requisite hip enlargement. This side section is padded, and may be 55 quilted, as shown, for preserving it against undue stretching and twisting, although desirably soft and flexible.

Heretofore padded front sections have been embodied in corsets; but, so far as my knowledge extends, no corset has heretofore been padded either at the side or adjacent to the hip-bone for producing the effect sought by me, as hereinafter fully set forth.

The back section, E, embraces the back bones 65 or steels, as usual, and extends from the top downward along the edge of the side section to the waist-line, and thence rearward and downward on a curved line to a point near the back bones at the lower edge of the corset. 70

Two hip-gores are employed on each side of the corset. The front hip-gore, F, occupies the triangular space in front of the side section, D, and the hip-gore F' the triangular space at the rear of the side section.

The padded side section, D, is stiffened throughout its length by a steel at its rear edge, d, and at its front edge, e, by two long bones, which extend from top to bottom of the corset. These side-section stiffeners diverge at the 80 waist, so as not to override the apex of the hip bone, but lie in front of and at the rear thereof, and they so distend the widened lower portion of said padded section as to prevent it from being unduly forced upward by the hip- 85 bone during the movements of the body.

The padded front sections, hereinbefore referred to as heretofore embodied in corsets, were also bounded on each side by vertical stiffeners, which diverged at the waist-line for 90 affording an intervening padded portion at the top for the accommodation of the breasts, and also at the bottom of the corset for accommodating the abdomen; but as heretofore used said padded front sections and their stiffeners 95 in no manner related to the ease and comfort of the wearer at the hip-joint, which is the main thing sought by me in this connection; nor did they render the corset comfortable beneath the arm, which is a minor point attained 100

by my padded side sections stiffened at each side by bones which diverge at the waist-line.

The corset at the junction of the side and front sections, C, with the front hip-gores, F, is stiffened by the angular or curved bones *f*, which extend from the waist-line at the edge of the padded section forward and downward to the lower edge of the corset near its front, and at the junction of the rear or back sections, E, with the rear hip-gores, F', it is stiffened by the curved bones *g*, which extend from the waist-line at the edge of the padded section rearward and downward to a point near the back steel at the lower edge of the corset. Each hip-gore is stiffened by vertical bones *h*, graduated in length, and extending vertically and parallel with each other from the curved bones *f* and *g*, respectively, to near the lower edge of the corset. The bones *i* of the front breast-sections, B, are also graduated in length, extending from the top edge of the corset to various points along the angular upper edge of the complex side and front section, C. The bones *k* of the sections C are also partially graduated in length. A few of these bones—three in this instance—extend from the top of the corset, adjacent to the outer side of the breast, downward alongside and thence beneath the breast-section and its bones to near the lower front edge of the corset. The remainder of the bones in this section extend from the top of the corset to various points along the angular or curved bones above the front hip-gore, F. The bones *l* in the back sections, E, are also graduated in length, and extend from the top edge of the corset to various points along the angular or curved bones *g* above the rear hip-gore, F'.

It will be seen that my corset, although well stiffened or stayed adjacent to the hips, can nevertheless snugly conform to that portion of the body without discomfort. The padded side section, although stiffened, allows the free movement of the upper portion of the body from

side to side without chafing at the hips. The arrangement of front and rear hip-gores, separated by the side section and its stiffeners, enables the free forward and rearward movement of the upper portion of the body without discomfort, and the hip-gores being separately stiffened afford the desirable supporting effect at the lower side portions of the corset and at the waist. The curved or angular stiffeners above the hip-gores admit of a desirable jointed action without impairing the bracing effect of the corset; and the same is true of the arrangement of the stiffeners in the side and front section, C, which are interposed between the breast-section and the front hip-gore.

Having thus described my invention, I claim as new and to be secured by Letters Patent—

1. The combination, in a corset having a side section stiffened at each edge from top to bottom of the corset, of front and rear hip-gores or sections, substantially as described.

2. The combination, in a corset, of a stiffened side section and stiffened hip-gores at the front and rear of the side section, substantially as described.

3. In a corset, the combination, with front and rear hip-gores having stiffeners *h* of vertical stiffeners or bones above the hip-gores and curved or inclined stiffeners interposed between the vertical stiffeners and the hip-gores, substantially as described.

4. In a corset, the combination of the stiffened breast-section, the stiffened front hip-gore, and the stiffened complex side and front section interposed between the breast-section and the front hip-gore, each of said sections and said front hip-gore having separate and independent groups of bones, substantially as described.

JULIUS HILBORN.
